UNITED STATES PATENT OFFICE.

ALBERT FRANCIS ALLEN, OF PROVIDENCE, RHODE ISLAND.

IMPROVEMENT IN FIRE-PLUGS AND HYDRANTS.

Specification forming part of Letters Patent No. 122,097, dated December 26, 1871.

To all whom it may concern:

Be it known that I, ALBERT FRANCIS ALLEN, of the city and county of Providence and State of Rhode Island, have invented certain new and useful Improvements in Hydrants and Fire-Plugs.

My invention consists in so controlling the delivery of the hydrant after water is let on from the mains and during the service of a fire-engine attached thereto, that a certain draughting or suction power will be requisite for taking from the hydrant a supply of water; and I do hereby declare that the following specification, taken in connection with the drawing furnished and forming a part of the same, is a clear, true, and exact description of a hydrant embodying my invention.

It is well known that a steam fire-engine, for instance, doing service at any hydrant through which water is freely flowing under the usual high pressure will experience more or less injury upon the suction-hose and pump-valves on account of the independent pressure exercised by the water between the hydrant and the pump-piston; that, instead of being contracted, as is the case during actual draughting service, the suction-hose is distended and weakened, the interior rings or ribs (when such are used) become misplaced, and the suction-valves of the pump become strained, for their independent closing power is less than the normal force of the water under pressure, and they can only be closed by the pressure within the pump induced by the action of the piston. It is obvious that this undue straining of the suction-valves and suction-hose must render the apparatus more or less unfit for efficient service in localities where there are no hydrants and where water must be raised by suction.

Referring to the drawing, Figure 1 represents, in perspective, a hydrant or fire-plug embodying my improvement. Fig. 2 represents the same in cross-vertical section. Fig. 3 represents, in vertical section, a hydrant-chamber, upon which one or more such hydrants may be mounted.

A represents the barrel of the hydrant. It can be made of any required length or diameter. In this instance it is represented as cylindrical and provided with a flange at the bottom for attachment to a hydrant-chamber, water-main, or branch. B represents the delivery-port cut through the barrel near its top, and provided with a screw-connection, as is usual in such cases. C represents a controlling-valve which guards the delivery-

port B. It is, in this instance, shown to be an ordinary ground-seat valve arranged to open outward. It is mounted on a horizontal valve-stem, c, extending both ways from the valve, outward as well as inward. The outer end of the valve-stem is fitted to a horizontal cylindrical bearing, a, which is sustained by arms extending radially from the interior walls of the delivery-port. D represents a piston or plunger, which is fitted to the interior of the upper end of the hydrant-barrel, which is of somewhat decreased diameter than the lower part, and is turned out properly to receive the piston. A number of annular recesses are cut in the vertical side of the piston, which, when charged with water, serve as frictionless packing. E represents a vertical connecting-lever, pivoted on a bearing located on the inner side of the barrel above the delivery-port B. The upper end of this lever is nearly horizontal, and passes through a slot in a stud, d, which projects downward from the center of the under side of the piston D. The lower end of the lever is nearly vertical, and passes through a slot in the inner end of the valve-stem c. F represents a cross-bar extending diametrically across the upper end of the hydrant-barrel. It sustains a cam-lever, G, which, when turned to the right, bears upon the top of the piston and holds it at its lowest point instead of allowing the pressure of the water to carry it to its highest elevation, which will readily follow if the cam-lever be turned to the left.

It will be seen that the movement of the piston D controls the valve C by means of the connecting-lever E. The area of the face of the piston should be greater than the area of the valve-opening at the delivery-port in order that the pressure operating upon both will cause the piston D to hold the valve C to its seat and prevent the delivery of water until, by the application of suction, the excess of pressure upon the piston D is overcome; or, when a free delivery is required direct from the hydrant, the valve will remain closed until opened by positive means—as, for instance, the downward pressure of the cam-lever G upon the piston D, which permits the valve to promptly open by the normal pressure of the water. An excess in the area of the piston of from one-quarter to one-half, as may be desired, will be found to secure good results, although a lesser excess will, in some cases, be sufficient. It is

evident that somewhat similar results may be accomplished by mounting upon the outer end of the controlling valve-stem *c* an expansive spiral spring, so set that it will force the valve *C* against its seat and keep it closed until the application of suction is made thereto. Should a spring be so employed, however, an independent means must also be provided for opening the valve when a free and direct delivery should be required—as, for instance, an auxiliary valve-rod with its inner end abutting against the inner end of the valve-stem *c*, and its outer end projecting through the opposite side of the barrel, and operated longitudinally by a screw and wheel in a manner well known. It will be obvious that, if a spring be used, that it must have a force greater than can ever be exercised by the water pressure from the mains; the greater the pressure in the mains, it is evident that the suction power requisite for opening the valve will be proportionately lessened; while, on the contrary, if the force or pressure in the main be lessened the requisite suction power will be proportionately increased. The greater the pressure on the main, it is evident that the necessity for exercising the draughting power of the engine is increased in order to prevent the pressure of the water from straining the suction-hose end valves. With the valve controlled as shown herein the greater the pressure may be in the mains the closer the controlling-valve will crowd its seat, and, therefore, the suction force required to obtain water from the hydrant will be proportionately increased.

When a steam fire-engine or pump is provided with an automatic relief-valve like those, for instance, patented by me April 18th and November 14th, 1871, or with a so-called circulating-valve, it will frequently occur that the pumps will be rendered inoperative, although still running and at unabated speed. In such instances, when used with hydrants as ordinarily constructed, the back or independent water pressure unavoidably causes undue strain upon both suction-hose and suction-valves, and, as it is, to a greater or lesser extent, a percussive force, it is especially liable to result in injury to the apparatus.

It is desirable that two or more hydrants be mounted upon one hydrant chamber with which a valve is combined and located at its connection with the main.

Any of the well-known forms of waste-water relief-valves may be applied for securing the free discharge of water from the hydrant-barrel and from the interior of the delivery-port when no longer needed, and after the supply has been cut off below in the hydrant-chamber. Such an arrangement will be essential during the winter season to prevent the hydrant from being closed by the freezing of the water which would otherwise be left therein.

The controlling valve, substantially as described, may be attached to the engine near the pump to protect the suction-valves; or it can be made separate, in an obvious manner, for temporary attachment to any hydrant when desired.

Having thus described my invention, I claim as new and desire to secure by Letters Patent—

1. A hydrant having its delivery-port guarded by a controlling-valve which is incapable of being opened by the normal pressure of water from the mains, and which requires the application of draughting power from a pump to induce the delivery of water, as and for the purposes specified.

2. The combination, within a hydrant, of the piston *D* and controlling-valve *C*, connected and operating substantially as described, and for the purposes specified.

3. The combination of the piston *D*, controlling-valve *C*, and cam-lever *G*, as and for the purposes specified.

4. In combination with a pump and hydrant, the controlling-valve *C*, arranged to remain closed by resisting the highest degree of water pressure, and capable of being opened by the power of suction applied in the usual manner, substantially as and for the purposes specified.

ALBERT F. ALLEN.
